METHOD OF AND APPARATUS FOR PRODUCING BIMETALLIC STRIPS

John V. O. Palm and George S. Salzman, Cleveland Heights, Ohio, assignors to The Cleveland Graphite Bronze Company, Cleveland, Ohio, a corporation of Ohio

Application March 3, 1933, Serial No. 659,478

6 Claims. (Cl. 29—33)

The present invention relating, as indicated, to a method of an apparatus for producing bi-metallic strip, is more particularly directed to an improved method and apparatus for the manufacture of a bi-metallic strip consisting of two dissimilar metals and to the production of a strip of this character to accurate and predetermined dimensions. In the manufacture of bi-metallic strip of the type in which a layer of a metal such as steel is coated with a layer of a softer material such as a bearing metal for subsequent manufacture into bearings, it is very desirable that not only the supporting metal, that is, the steel, but also the bearing metal be accurately finished to exact and predetermined limits in order to insure accurate final articles and one in which the layer or coating of bearing metal will be of uniform thickness. This has been difficult to accomplish and has resulted in past processes in the production of excessive amounts of scrap.

Our present invention makes it possible to provide a bi-metallic strip of exact and predetermined dimensions. To the accomplishment of the foregoing and related ends, said invention, then, consists of the means hereinafter fully described and particularly pointed out in the claims, the annexed drawing and the following description setting forth in detail certain means and one mode of carrying out the invention, such disclosed means and mode illustrating, however, but one of various ways in which the principle of the invention may be used.

In said annexed drawing:

Fig. 1 is a side elevation more or less diagrammatic in character illustrating an apparatus adapted to carry out the steps of our improved method; Figs. 2, 3 and 4 are sections on the lines 2—2, 3—3, and 4—4 respectively.

It will be understood that the use of the term "steel" in the following description and claims denotes any suitable metal employed as the backing or reenforcing strip of the bi-metallic element to be produced and of course other materials such, for example, as bronze and similar metals may for certain purposes be substituted as a re-enforcing metal. Similarly, the term "bearing metal" or "babbitt" as hereinafter used is intended to refer to any suitable metal softer than the reenforcing or backing metal and having a lower melting point.

Referring now to Fig. 1, we have shown a steel strip 1 which is passed through a chamber 2 in which there is maintained a bath of molten babbitt which is maintained in contact with the upper portion and preferably a predetermined

part of the upper portion only of the steel strip 1. The strip 1 as it issues from the chamber 2 is provided with a coating 3 of babbitt which may be solidified by any suitable means to produce a bi-metallic strip 4 of steel and babbitt. This strip is then passed through a brake or a drag consisting of shoes 5 and springs 6 which exert a resistance to movement of the bi-metallic strip. The strip passes from the drag described over a supporting roll 7 and beneath a milling roll or cutter 8, then over a second supporting roll 9 and a second milling roll 10 and then through pulling rolls 11 after which the bi-metallic strip is wound into a coil 12 for storage and subsequent use.

The bi-metallic strip as it issues from the molten babbitt chamber is in the form illustrated in Fig. 2 in which the babbitt 3 is confined to the central portion of the steel strip 1, the edges 13 of the strip having been blanked off during the passage of the strip through the bath to prevent leakage of the babbitt around the edges of the strip and between the bottom of the strip and the supporting bottom of the chamber 2. The babbitt on the strip at this stage is slightly thicker than the required coating and while the steel strip is ordinarily fairly accurate in thickness and uniform in contour it is sometimes slightly concave and is also very slightly warped by reason of the heating in the babbitt chamber. It is impossible to accurately machine the babbitt coating to produce a uniform thickness unless the irregularities in the steel are removed or compensated for, and as these irregularities are not uniform they cannot of course be compensated for even if this were a commercial operation. We have found, however, that by placing the composite strip under a heavy tension the irregularities in the strip can be smoothed out and that the coating of babbitt can be machined, while the strip is in this condition, to an accurate finish and to an accurate and predetermined thickness. We accomplish this by placing the composite strip under severe tension produced by the drag 5 and the pulling rolls 11 and causing the strip at the same time to be bent out of its normal position by passage over the supporting rolls 7 and 9. The cutter 8 takes a roughing cut from the surface of the babbitt while the cutter 10 completes the operation, each cutter removing but very little stock and producing an extremely accurate and smooth surface and at the same time providing a uniform thickness of babbitt coating on the steel. We have found it necessary to em- 110

ploy a severe tension on the strip which of course must be varied, depending upon the thickness, tensile strength, and width of the strip, but must in all cases be sufficient to tension the strip so that its entire width is in contact with the supporting roll at the point of machining. The result is a bi-metallic strip of the type shown in Fig. 4 which has been brought to a uniform thickness and smooth surface. Subsequently, if desired, the edges of the strip may be removed to make the width of the babbitt co-extensive with the width of the supporting strip.

Other modes of applying the principle of our invention may be employed instead of the one explained, change being made as regards the means and the steps herein disclosed, provided those stated by any of the following claims or their equivalent be employed.

We therefore particularly point out and distinctly claim as our invention:—

1. In a method of making bi-metallic strip, the steps which consist in integrally uniting a coating of bearing metal to one surface of a strip of steel, converting the steel strip to a substantially flat level condition and simultaneously removing part of the coating applied thereto.

2. In a method of making bi-metallic strip, the steps which consist in bonding a coating of bearing metal to one surface of a strip of steel, tensioning the composite strip thus formed to a substantially flat level condition and then removing a predetermined portion of the bearing metal coating from the tensioned strip.

3. In apparatus of the character described, the combination of means adapted to engage a bi-metallic strip at spaced points longitudinally thereof to move said strip, and simultaneously subject the same to flattening tension, and cutting means disposed between said first-named tensioning means, said cutting means being

adapted to successively condition one surface of the tensioned portion of said strip.

4. In apparatus of the character described, the combination of means adapted to engage a bi-metallic strip at points spaced longitudinally thereof, said means being adapted to progressively move said strip longitudinally and simultaneously subject the same to flattening tension, and cutting means disposed between said first-named tensioning means and adapted to machine one surface of the tensioned portion of said strip.

5. In apparatus of the character described, the combination of retarding means adapted to engage a bi-metallic strip, pulling means also adapted to engage a bi-metallic strip at a point spaced from said retarding means for moving such strip longitudinally, said pulling and retarding means being conjointly adapted to exert a flattening tension on a composite strip engaged thereby, and means adapted to remove material to a predetermined point along one surface of such strip while the latter is subjected to such flattening tension.

6. In apparatus of the character described, the combination of retarding means adapted to engage a bi-metallic strip passing therebetween, pulling means also adapted to engage a bi-metallic strip and move the same longitudinally against the action of said retarding means, said retarding and pulling means being conjointly adapted to exert a flattening tension on such composite strip, and means engaging one surface of said strip at a point intermediate said retarding and pulling means to angularly bend said strip and other means adapted to machine the surface of said strip opposite to said last-named means at such point of bend.
